LOOM SHUTTLE STRUCTURE

Herman Nova, Woonsocket, R. I., assignor to
 Shambow Shuttle Company, Woonsocket, R. I.,
 a corporation of Rhode Island

Application July 7, 1933, Serial No. 679,357

1 Claim. (Cl. 139—217)

This invention relates to an improved loom shuttle structure, such as is particularly adapted for use in weft replenishing looms and involves a new and improved arrangement of the parts 5 in connection with a tensioning element for rendering the tension effective on the first pick after transfer.

One object of the invention is the provision of a loom shuttle structure of this character where- 10 in the tensioning means is so positioned with relation to the thread block as to be effective immediately for the application of tension to the thread even before the thread is positioned within the thread eye.

Another object of the invention is the provi- 15 sion in a device of this character of a thread passage located in operative relation with the thread eye and so formed as to have a tendency to resist looping of the thread as well as its ac- cidental escape from the thread passage while 20 the shuttle is in operation.

A further object of the invention is the pro- 25 vision in a device of this character of separate tension members mounted for rectilinear move- ment transversely of the path of travel of the thread and so positioned as to receive the thread and be effective for applying tension thereto on the first pick after transfer, together with a thread passage located between the tension 30 members and the thread eye, so shaped as to insure a continuous and proper delivery of the tension thread to the thread eye in such a manner that the thread will be delivered under sub- stantially uniform tension.

Other objects and advantages of the invention 35 relate to various improved details of construction and novel forms and arrangements of the parts as will be more fully set forth in the detailed description to follow.

Referring to the drawing:—

Fig. 1 is a top plan view of the thread delivery 40 end of a loom shuttle of the type adapted for use in weft replenishing looms, and embodying one form of my improved structure,

Fig. 2 is a vertical sectional view through the shuttle end shown in Fig. 1, taken substantially 45 through the thread receiving channel of the thread block,

Fig. 3 is a side elevational view of the thread 50 block illustrating the same as it appears when removed from the shuttle,

Fig. 4 is a vertical transverse sectional view 55 through the thread block, taken substantially along the line 4—4 of Fig. 3,

Fig. 5 is a vertical transverse sectional view

through the thread block, taken substantially along the line 5—5 of Fig. 3, and,

Fig. 6 is a perspective view of one of the ten- 5 sion members.

In that form of the invention illustrated here- 10 with 1 designates a loom shuttle body provided with a central opening 2 extending therethrough as is usual in weft replenishing loom shuttles, and having a bobbin 3 mounted within the open- 15 ing 2 in the usual manner with weft thread 4 wound thereon for delivery to the weave as is usual in devices of this character.

A thread block 6 is suitably secured within a 15 thread block opening 7 formed in the shuttle body and communicating with the central open- 20 ing 2 as is common in devices of this character.

The thread block 6 is provided with a thread 25 receiving channel 8 extending substantially lon- gitudinally thereof, the lower portion of which forms a normal thread passage 9 separated from 30 the upper portion thereof by means of longi- tudinal ribs 10, thus forming a thread passage 35 extending throughout the major portion of the thread block, which may be of a substantially circular contour in cross section to better retain 40 the thread therein and prevent it from "ballooning" or escaping from the thread passage proper when slackness occurs in the thread as during the changing of the direction of movement of the shuttle. The thread block is also provided 45 with a downwardly and forwardly inclined leader 11, and a downwardly inclined end portion 12 which normally extends beneath an overhanging ledge 14 carried by the thread block and located upon the opposite side of the channel 8. The 50 leader 11 and downwardly inclined end portion 12 of the thread block tend to guide the weft thread downwardly into the normal thread pas- 55 sage 9, as tension is exerted upon the weft thread by the tension members immediately after transfer, to insure proper location of the weft thread within the passage 9, and these ele- ments also serve to prevent escape of the weft thread from the passage 9 in the normal opera- tion of the shuttle.

A pair of tension members or plates 15 are mounted for sliding movement upon a shaft 16 extending transversely of the shuttle body, and the tension members 15 are each provided with a laterally bent end portion 17. The lat- 50 erally bent end portions 17 are adapted for mounting in opposed openings 18 and 19 formed in the thread block and serve as guiding and supporting means for assisting in maintaining the tension members 15 in opposed relation 55

with each other while permitting free rectilinear movement of the tension members towards and from each other in a direction transversely of the thread passage 9. A tensioning screw 20 is threaded within one side of the thread block and in opposed relation with one of the tension members, and the tensioning screw 20 may be provided with a reduced central portion 21 for supporting and guiding a coiled spring 22 which is adapted to bear against one of the tension members 15 for resiliently urging the tension members towards each other. The coiled spring 22 may be positioned to engage the tension member 15 substantially midway between the shaft 16 and the laterally bent portion 17 whereby the requisite degree of tension is applied to that portion of the tension member opposite the thread passage 9, and at the same time resistance is provided against upward movement of the thread between the tension members after the thread has once been positioned within the passage 9, to tend to prevent escape of the thread from between the tension members or from the thread channel during the operations of the shuttle.

A detent 24 may be provided with a rib 25 adapted to fit within the slotted end of the adjusting screw 20 and may be pivotally mounted, as at 26, in such a manner as to be movable into position for the engagement of the rib 25 within the slot 27 in the end of the tension screw 20 before the thread block 6 is inserted within the thread block opening 7 of the shuttle. Upon removal of the thread block 6 from the shuttle body the tension screw 20 may be set as is desired to impart the required degree of tension to the tension members for the type and size of weft thread employed.

Steel bushings 29 may be inserted in the opposed openings 18 and 19 formed in the thread block to prevent undue wear of the thread block by the laterally bent portions 17 of the tension members 15.

The substantially enclosed character of the thread passage 9 in conjunction with the provision of the downwardly inclined leader 11 and the inclined end portion 12 extending beneath the ledge 14 practically prevents the escape of the weft thread after its insertion within the thread passage 9, while the particular form and construction of the inclined leader 11 and downturned end 12 are such as to offer no obstruction to the entrance of the thread into the thread passage 9, but on the contrary serve to positively guide the thread 4 into the passage as tension is applied to the thread.

While I have shown and described a single tension spring 22 positioned for engagement with one of the tension members 15, it is to be understood that any suitable or equivalent resilient means may be similarly positioned with reference to the other tension member 15 whereby positive tension may be applied to both of the tension members whenever it may be found desirable. The degree of tension exerted by the spring 22 may be varied as indicated by properly setting the screw 20 and then holding the screw against rotation while the shuttle is in use by means of the detent 24, and, if desired, the spring or springs 22 may be changed when necessary to provide greater or less tensioning effect on the members 15 as may be desired.

In order to obtain substantially uniform and immediately effective tension upon the weft thread during the operation of the shuttle, and

on the first pick after transfer, the tension members 15 are located rearwardly of the thread passage 9 in the thread block and are extended upwardly from the level of the thread passage sufficiently to be substantially completely effective for applying the desired degree of tension to the weft thread upon the commencement of movement of the shuttle after transfer and before the weft thread is completely drawn within the thread passage 9, as is shown more particularly in Fig. 2 of the drawing. The location of the tension members 15 rearwardly of the thread block from the thread eye, and the rounded formation of the upper end portions 28 thereof, insure the positive guidance of the weft 15 thread into tensioned position between the tension members and the proper application of tension thereto immediately upon the beginning of the shuttle movement after transfer.

The relatively considerable extent of the tension members 15 above the thread passage 9 and the rounded portion 28 of the tension members causes the weft thread 4 to be automatically drawn into position between the tension members upon the first movement of the shuttle after transfer, after the manner shown in Fig. 2 of the drawing, and before the weft thread is drawn into the thread passage 9. It will be noted also upon reference to Fig. 2 of the drawing that as the weft thread 4 is drawn into 30 position between the tension members 15 upon the first movement of the shuttle after transfer, it is drawn downwardly into a position substantially opposite to the point of application of the tension spring 22, whereby the tension exerted 35 upon the weft thread 4 on the first pick after transfer, and before the weft thread is drawn into the thread passage 9 for delivery from the thread eye, is substantially the same as the tension to which the thread is subjected after being 40 positioned within the thread passage. This tends to produce substantially complete uniformity in the weave since the tension effective upon the weft thread during the first movement of the thread after transfer is substantially the 45 same as that exerted thereon after the weft thread enters the thread passage 9 for delivery from the thread eye in the normal continued operation of the shuttle.

The location of the tension members 15 relative to the thread block and their extent above the thread passage as well as the position of the tension spring with reference thereto enables the thread to be drawn into tensioned position between the tension members on the first movement of the shuttle after transfer and provides for the application of normal tension to the thread on the first pick after transfer.

What I claim is:—

In a weft replenishing loom shuttle provided with means for exerting substantially normal tension upon a thread before the thread is drawn into the thread delivery eye, a thread block provided with a normal thread passage communicating directly with the thread delivery eye and having a restricted thread receiving opening communicating therewith through which the thread is drawn into thread passage for entry into the thread delivery eye, means for pretensioning the thread prior to its being drawn 70 into the thread delivery eye to an extent substantially equivalent to the tension exerted upon the thread when located within the thread passage and thread delivery eye comprising, upright tension members located at the bobbin end of 75

5 said thread passage and having contact surfaces extending materially above said thread passage for receiving and tensioning a thread above said normal thread passage on the first pick after transfer, said tension members being supported at a point in the same horizontal plane as the lower portion of said normal thread 10 passage for combined sliding and tilting movement transversely of said thread passage, and resilient means engaging one of said tension

members at a point in the same horizontal plane as the upper edge of the normal thread passage and substantially midway between the point of support for said tension member and the location of the thread when initially subjected to 15 tension as it is drawn between the tension members at the commencement of the shuttle movement on the first pick after transfer.

HERMAN NOVA. 10
